PAGE 2

FIG. 7

FIG. 9

FIG. 1 is a top plan view in closed position of a pencil box, showing our new design;

FIG. 2 is a side elevational view thereof, the opposite side being the same;

FIG. 3 is an elevational view of the upper end of FIG. 1;

FIG. 4 is an elevational view of the lower end of FIG. 1;

FIG. 5 is a rear elevational view thereof;

FIG. 6 is an internal plan view in full open position of the box shown in FIG. 1;

FIG. 7 is a perspective view of the box with the top open and the bottom closed;

FIG. 8 is a front perspective view of the box in operative condition with the top portions folded upon its hinge to form an easel support;

FIG. 9 is a rear perspective view similar to FIG. 8; and

FIG. 10 is a section taken on line 10—10 of FIG. 1.

We claim:

The ornamental design for a pencil box, as shown and described.
